(57) **ABSTRACT**

A treadmill may include a platform, at least one pulley attached to the platform, a sliding surface of the platform, a tread belt riding portion of the sliding surface, a tread belt surrounding the pulley and the sliding surface, the tread belt having at least one side edge, and a belt guide incorporated into the platform. The belt guide includes a textured portion of the sliding surface aligned with the side edge of the tread belt and spaced apart therefrom when the tread belt is positioned entirely within the tread belt riding portion. When the textured portion comes into contact the tread belt from the tread belt being misaligned out of the tread belt riding portion, the tread belt and the textured portion collectively produce a misalignment sound audible to a user when the tread belt moves against the sliding surface.

AUDIBLE BELT GUIDE IN A TREADMILL

BACKGROUND

Aerobic exercise is a popular form of exercise that improves one's cardiovascular health by reducing blood pressure and providing other benefits to the human body. Aerobic exercise generally involves low intensity physical exertion over a long duration of time. Typically, the human body can adequately supply enough oxygen to meet the body's demands at the intensity levels involved with aerobic exercise. Popular forms of aerobic exercise include running, jogging, swimming, and cycling, among others activities. In contrast, anaerobic exercise typically involves high intensity exercises over a short duration of time. Popular forms of anaerobic exercise include strength training and short distance running.

Many choose to perform aerobic exercises indoors, such as in a gym or their home. Often, a user will use an aerobic exercise machine to have an aerobic workout indoors. One type of aerobic exercise machine is a treadmill, which is a machine that has a running deck attached to a support frame. The running deck can support the weight of a person using the machine. The running deck incorporates a conveyor belt that is driven by a motor. A user can run or walk in place on the conveyor belt by running or walking at the conveyor belt's speed. The speed and other operations of the treadmill are generally controlled through a control module that is also attached to the support frame and within a convenient reach of the user. The control module can include a display, buttons for increasing or decreasing a speed of the conveyor belt, controls for adjusting a tilt angle of the running deck, or other controls. Other popular exercise machines that allow a user to perform aerobic exercises indoors include elliptical trainers, rowing machines, stepper machines, and stationary bikes to name a few.

In some cases, the conveyor belt may move slightly out of its desired position during the normal course of use of the treadmill such that it may rub against some portion of the treadmill. This unintended rubbing may go unnoticed by a user and may wear out the belt more quickly than if it were in its desired position, leading to a more frequent need to replace the belt and higher maintenance costs for the user.

SUMMARY

In one embodiment, a treadmill includes an exercise deck. The exercise deck includes a platform, at least one pulley attached to the platform, a sliding surface of the platform, a tread belt riding portion of the sliding surface, a tread belt surrounding the at least one pulley and the sliding surface, the tread belt having at least one side edge, and a belt guide incorporated into the platform. The belt guide includes a textured portion of the sliding surface aligned with the at least one of side edge of the tread belt and spaced apart therefrom when the tread belt is positioned entirely within the tread belt riding portion. When the textured portion comes into contact with the tread belt, due to the tread belt being misaligned, the tread belt and the textured portion interact to collectively produce a misalignment sound audible to a user, providing an audible indicator of tread belt misalignment.

The textured portion may include a plurality of protrusions.

The textured portion may include a plurality of ribs.

The plurality of ribs may be arranged perpendicular to the at least one edge of the tread belt.

The textured portion may include a rough surface having a root mean square surface roughness of more than about 5 microns.

The textured portion may include a patterned surface.

5 The belt guide may include a lip portion extending over at least a portion of the at least one edge of the tread belt.

The textured portion may be positioned above the at least one edge of the tread belt.

10 The tread belt and the tread belt riding portion may collectively produce an operational sound audible to a user when the tread belt is in motion with respect to the sliding surface when the tread belt is not in contact with the textured portion. The operating sound may produce a different frequency than the misalignment sound.

15 The belt guide may include a raised ledge aligned with the at least one edge of the tread belt.

The textured portion may contact the at least one edge of the tread belt to mechanically produce the misalignment sound when the tread belt is in motion around the sliding surface and at least a portion of the tread belt is positioned outside the tread belt riding portion.

20 The textured portion may contact an interior pulley facing surface of the tread belt to mechanically produce the sound audible to the user when the tread belt is in motion around the at least one pulley and at least a portion of the tread belt is positioned outside the tread belt riding portion.

25 The misalignment sound may not be produced when no portion of the tread belt is positioned outside the tread belt riding portion.

30 The misalignment sound may be distinguishable by a user from routine operating sounds of the treadmill produced when the tread belt is entirely positioned within the tread belt riding portion.

In one embodiment, a treadmill includes an exercise deck.

35 The exercise deck includes a platform, at least one pulley attached to the platform, a sliding surface of the platform, a tread belt riding portion defined in the sliding surface, a tread belt surrounding the at least one pulley where the tread belt has at least one edge, and a belt guide incorporated into the platform. The belt guide may include a textured portion aligned with the at least one edge of the tread belt and spaced apart therefrom when the tread belt is positioned within the tread belt riding portion. The textured portion contacts a portion of the tread belt mechanically producing a misalignment sound audible when the tread belt is in motion with respect to the sliding surface and at least a portion of the tread belt is positioned outside the tread belt riding portion. The misalignment sound may not be produced when the tread belt is positioned entirely within the tread belt riding portion and the misalignment sound is distinguishable from a routine operating sound of the treadmill.

40 The belt guide may include a lip portion extending over at least a portion of the at least one edge of the tread belt.

The textured portion may be positioned above the at least one edge of the tread belt.

45 The belt guide may include a raised ledge aligned with the at least one edge of the tread belt.

The textured surface may engage an underside surface of the tread belt when the tread belt is misaligned out of the tread belt riding portion.

50 In one embodiment, a treadmill includes an exercise deck. The exercise deck includes a platform, a first pulley attached to the platform in a front portion, a second pulley attached to the platform in a rear portion, a sliding surface of the platform, a tread belt riding portion of the sliding surface, a tread belt surrounding the first pulley, the second pulley, and the sliding surface, the tread belt having at least one edge

and a top surface, and a belt guide incorporated into the platform. The belt guide includes a lip portion extending over at least a portion of the at least one edge of the tread belt. A textured portion includes a rough surface, the textured portion aligned with and positioned above the at least one edge of the tread belt and spaced apart therefrom when the tread belt is positioned within the tread belt riding portion. The textured portion contacts the top surface of the tread belt to thereby mechanically produce a misalignment sound audible to a user when the tread belt is in motion with respect to the sliding surface of the platform and at least a portion of the tread belt is positioned outside the tread belt riding portion. The misalignment sound is not produced when the tread belt is positioned entirely within the tread belt riding portion and the misalignment sound is distinguishable by the user from a routine operating sound of the treadmill.

BRIEF DESCRIPTION OF THE DRAWINGS

The accompanying drawings illustrate various embodiments of the present apparatus and are a part of the specification. The illustrated embodiments are merely examples of the present apparatus and do not limit the scope thereof.

FIG. 1 illustrates a perspective view of an example of a treadmill in accordance with the present disclosure.

FIG. 2 illustrates a perspective view of an example of a treadmill in accordance with the present disclosure.

FIG. 3 illustrates a top view of an example of a treadmill in accordance with the present disclosure.

FIG. 4 illustrates a side view of an example of a treadmill in accordance with the present disclosure.

FIG. 5A illustrates a cross sectional view along line A-A of the example treadmill of FIG. 4 and in accordance with the present disclosure.

FIG. 5B illustrates a close up of the example depicted in FIG. 5B and in accordance with the present disclosure.

FIG. 6 illustrates an example of a belt guide incorporated into the top portion of the treadmill deck in accordance with the present disclosure.

FIG. 7 illustrates an example of a belt guide incorporated into the top portion of the treadmill deck in accordance with the present disclosure.

FIG. 8 illustrates an example of a belt guide incorporated into the top portion of the treadmill deck in accordance with the present disclosure.

FIG. 9 illustrates an example of a belt guide incorporated into the top portion of the treadmill deck in accordance with the present disclosure.

FIG. 10 illustrates an example of a location of a textured portion in accordance with the present disclosure.

FIG. 11 illustrates an example of a location of a textured portion in accordance with the present disclosure.

FIG. 12 illustrates an example of a location of a textured portion in accordance with the present disclosure.

FIG. 13 illustrates an example of a textured portion in accordance with the present disclosure.

FIG. 14 illustrates an example of a textured portion in accordance with the present disclosure.

FIG. 15 illustrates an example of a textured portion in accordance with the present disclosure.

Throughout the drawings, identical reference numbers designate similar, but not necessarily identical, elements.

than 35.0 degrees. For purposes of this disclosure, the term “transverse” means perpendicular, substantially perpendicular, or forming an angle between 55.0 and 125.0 degrees. Also, for purposes of this disclosure, the term “length” means the longest dimension of an object. Also, for purposes of this disclosure, the term “width” means the dimension of an object from side to side. For the purposes of this disclosure, the term “above” generally means superjacent, substantially superjacent, or higher than another object although not directly overlying the object. Further, for purposes of this disclosure, the term “mechanical communication” generally refers to components being in direct physical contact with each other or being in indirect physical contact with each other where movement of one component affect the position of the other.

The term “tread belt riding portion” generally refers to a portion of the sliding surface that is intended for the tread belt to slide on. In some cases, the tread belt riding portion includes a smooth surface with relatively low amounts of friction against which the tread belt can slide across. In some cases, the sliding portion is framed with a lip or ledge on either side of the sliding portion, but the “tread belt riding portion” may be narrower than the entire sliding area. In some cases, a textured portion abuts the “tread belt riding portion” on at least one side.

FIG. 1 depicts an example of a treadmill 100 having a deck 102 with a first pulley 103 disposed in a first portion of the deck 102 and a second pulley incorporated into a second portion of the deck 102. A tread belt 104 surrounds the first pulley and the second pulley. A motor 106 is in mechanical communication with either the first pulley or the second pulley. A cover 108 is superjacent the motor 106.

The treadmill 100 also includes at least one belt guide 110 that may audibly indicate to a user when the tread belt 104 is off-center, off-canter, or otherwise displaced from a belt riding portion of the first and/or second pulley while in motion. For example, the belt guide 110 may mechanically produce a sound that is audible to a user when the tread belt 104 is off-center or otherwise out of position around the first and/or second pulleys.

FIG. 2 depicts an example of a treadmill 200 that includes a deck 202 and an upright structure 204. The upright structure 204 includes a console 206 and incorporates at least one input mechanism 208 and a display 210. The input mechanism 208 can control at least one parameter of the treadmill, such as the speed of the tread belt 214, the incline of the deck 202, a climate control, entertainment, and so forth.

The deck includes a platform 212 with a front pulley and a rear pulley. A tread belt 214 surrounds the front and rear pulleys. The platform 212 includes portions of the deck 202 that are adjacent to the tread belt's edges. In the example of FIG. 2, these regions may include a belt guide 216 that overlaps with a portion of the tread belt. A textured portion (not shown) may be incorporated into an underside with the belt guide 216 so that when the tread belt 214 is misaligned, the tread belt 214 and the textured portion come into contact with each other.

FIG. 3 depicts a top view of an example deck 300 and the belt guides 302 of the platform. As illustrated, in some cases the deck 300 may include a belt guide 302 on the left side 306 and/or the right side 310 of the deck 300. In some cases at least one of the belt guides 302 include a textured portion which may mechanically produce an audible sound when contacted by the tread belt 304 while the tread belt 304 is displaced or otherwise out of position as described herein. In some cases both belt guides 302 on sides 306 and 310 may

DETAILED DESCRIPTION

For purposes of this disclosure, the term “aligned” means parallel, substantially parallel, or forming an angle of less

include a textured portion as described herein. For illustrative purposes, a user's first foot is represented with a first foot print 312 and a user's second foot is represented with a second foot print 314.

In some cases, the textured portion of the belt guide or guides 302 may be positioned at any position along the length of the belt guide 302 and may be aligned with an edge 305 of the tread belt 304. In some cases the textured portion of the belt guide may run an entire length of the belt guide 302. However in some other cases, the textured portion may extend along between about half of the length of the belt guide 302 and the entire length of the belt guide 302. In some cases the textured portion may extend along less than about half of the length of the belt guide 302, for example about $\frac{1}{3}$, $\frac{1}{4}$, $\frac{1}{8}$, $\frac{1}{16}$, $\frac{1}{32}$ or less of the length of the belt guide. In some embodiments the textured portion may not include one continuous portion and may be divided by one or more untextured portions of the belt guide 302. For example, the textured portion may include a first portion located near a first end of the belt guide 302 and a second textured portion located near a second end of the belt guide.

FIG. 4 depicts a side view of an example treadmill 400 as described herein with a deck 402 including a tread belt 404. FIG. 5A depicts a cross sectional view along line A-A of FIG. 4, showing the tread belt 404, as well as a belt guide 406 on both sides 408, 410 of the deck 402. In some cases, and as illustrated in FIG. 5A, the belt guide or guides 406 may be located to come into contact with the underside of the pulley. In some cases, the belt guide 406 may come into contact with underside of the deck's platform. FIG. 5B depicts a close up of the belt guide 406 depicted in FIG. 5A. In this example, the tread belt 404 is depicted with a top portion 404a over the sliding surface of the treadmill deck and a bottom portion 404b that is below the underside of the sliding surface 412. In this example, the belt guide 406 is located to make contact with the bottom portion 404b of the tread belt 404.

The belt guide 406 may be positioned away from the tread belt 404 when the tread belt is exactly centered on the sliding surface 412, but close enough so that when the tread belt 404 comes off of the riding portion 412, the edge of the tread belt 404 makes contact with the belt 406 and prevents the tread belt 404 from sliding off center even more. The belt guide 406 may be positioned to prevent the edge of the top portion 404a of the tread belt 404 from coming into contact with the deck rail 450. Preventing the tread belt 404 from contacting the deck rail 450 prevents damage to the deck rail 450 and to the tread belt 404.

In some cases, the belt guide 406 is spring loaded so that the belt guide 406 can exert a stronger realignment force on the tread belt 404 as counter forces increasingly push the tread belt off center. In some cases, the belt guide 406 is made of a sacrificial material that can be replaced if the belt guide 406 is worn down. In yet another example, the belt guide 406 may include a wear resistant material and/or wear resistant coating that can withstand a high amount of friction and/or heat.

FIG. 6 illustrates an alternative embodiment where the belt guide 406 is incorporated into the rear cover of the deck's platform. As described herein, a portion of the tread belt 404 is overlaid on the sliding surface of the platform and resides entirely within the central tread belt riding portion 413 of the sliding surface. In some cases, when the tread belt 404 stays entirely within the tread belt riding portion 413 while in motion the life of the tread belt 404 may be prolonged. In some cases, the tread belt riding portion 413 may be wider than the tread belt 404 to allow for some

amount of lateral or vertical displacement of the tread belt 404 without causing undue wear.

However, in some situations the tread belt may become displaced and some portion of it may become positioned outside of the tread belt riding portion 413. The potential displacement directions of the tread belt 404 are indicated with arrows. For example, in some situations the tread belt may become laterally displaced, as indicated with the rightward facing arrow, such that an edge of the tread belt 404 extends outside of the tread belt riding portion. In other cases, the tread belt 404 may become off-center, vertically displaced, or some combination of vertically and laterally displaced, as indicated with arrows. For example, due to a fold in the tread belt 404, lateral forces from a user, or any other mechanism of action may cause a distortion in the belt's alignment. Again, this displacement may lead the tread belt 404 to rub against or otherwise contact portions of the treadmill 400 outside of the tread belt riding portion 413 such that the tread belt will experience undesirable amounts of wear.

FIGS. 7-9 depict various cases and embodiments where the tread belt 404 has become displaced such that a portion of the tread belt 404 is not within the tread belt riding portion 413. In FIGS. 7-9, the tread belt 404 is displaced such that a portion of the tread belt 404 contacts a textured portion of the belt guide 406 to thereby mechanically produce a sound audible to and distinguishable by a user when the tread belt 404 is in motion.

FIG. 7 depicts the treadmill 400 substantially similar to the treadmill depicted in FIGS. 4-6, including belt guide 406 with a textured portion at location 414. In contrast to FIG. 6, the tread belt 404 has become laterally displaced outside of the tread belt riding portion 413 of the sliding surface 412. As indicated by the arrow, an edge of the tread belt 404 may contact with the textured portion at location 414. When the tread belt 404 is in motion, the edge of the tread belt 404 rubs against the textured portion at location 414 to thereby mechanically produce a sound audible to and distinguishable by a user. While FIGS. 6 and 7 depict a belt guide 406 on one side of the treadmill 400, in some cases the opposing side of the treadmill 400 may also include a belt guide 406 having a textured portion at location 414. The inclusion of a second belt guide 406 may thus enable the treadmill to mechanically produce a noise when the tread belt 404 is laterally displaced in two directions.

FIG. 8 depicts the treadmill 400 substantially similar to the treadmill depicted in FIGS. 4-6, including belt guide 406 with a textured portion at location 415. In this embodiment, the textured portion is positioned such that vertical displacement of the tread belt 404 may cause a portion of the tread belt 404 to contact the textured portion at location 415, as indicated by the arrow. When the tread belt 404 is in motion the top surface of the tread belt 404 rubs against the textured portion at location 415 to thereby mechanically produce a sound audible to and distinguishable by a user. In some embodiments where the belt guide 406 includes a lip, as depicted in FIG. 8, the lip may be low enough such that the top surface of the tread belt 404 may contact the lip and textured portion at location 415 when the tread belt 404 is laterally displaced and is not vertically displaced.

FIG. 9 depicts the treadmill 400 substantially similar to the treadmill depicted in FIGS. 4-6, including belt guide 406 with a textured portion at location 416. In this embodiment, the textured portion may be located on a surface of the sliding surface 412 outside of the tread belt riding portion 413. In some other embodiments, a portion of the belt guide 406 may be disposed over the sliding surface 412 at least at

location 416 and may include the textured portion. As indicated by the arrow, an interior surface of the tread belt 404 may contact with the textured portion at location 414. When the tread belt 404 is in motion, at least a portion of the interior surface of tread belt 404 rubs against the textured portion at location 416 to thereby mechanically produce a sound audible to and distinguishable by a user. While FIGS. 6 and 9 depict a belt guide 406 on one side of the treadmill 400, in some cases the opposing side of the treadmill 400 may also include a belt guide 406 having a textured portion at location 416. The inclusion of a second belt guide 406 may thus enable the treadmill to mechanically produce a noise when the tread belt 404 is laterally displaced in two directions.

FIG. 10 depicts an example of a tread belt 1000 with an edge 1002 that resides in a recessed region 1004 of the sliding surface 1006. The recessed region 1004 includes a bottom surface 1008 and a side wall 1010. In this example, a textured portion 1012 is located on the bottom surface 1008 adjacent to the side wall 1010. In this embodiment, when the tread belt 1000 misaligns by sliding towards the side wall 1010, the underside 1014 of the tread belt 1000 slides over the textured portion 1012. Collectively, the movement between the textured portion 1012 and the underside 1014 of the tread belt 1000 produce the misalignment sound.

FIG. 11 depicts an example of a tread belt 1100 with an edge 1102 that resides in a recessed region 1104 of the sliding surface 1106. The recessed region 1104 includes a bottom surface 1108 and a side wall 1110. In this example, a textured portion 1112 is located on the side wall 1110. In this embodiment, when the tread belt 1100 misaligns by sliding towards the side wall 1110, the edge 1102 of the tread belt 1100 slides into the textured portion 1112. Collectively, the movement between the textured portion 1112 and the edge 1102 of the tread belt 1100 produce the misalignment sound.

FIG. 12 depicts an example of a tread belt 1200 with an edge 1202 that resides in a recessed region 1204 of the sliding surface 1206. The recessed region 1204 includes a bottom surface 1208 and a side wall 1210. A cover 1209 may be placed to cantilever over the side wall 1210 over the edge 1202 of the tread belt 1200. In this example, a textured portion 1212 is located on the underside 1214 of the cover 1209. In this embodiment, when the tread belt 1200 misaligns by sliding towards the side wall 1210, the top surface 1216 of the tread belt 1200 slides into contact with the textured portion 1212. Collectively, the movement between the textured portion 1212 and the edge 1202 of the tread belt 1200 produce the misalignment sound.

In relation to the examples above, the textured portion may be formed in the platform, sliding surface, cover, or other component of the platform. In other examples, the textured portion is adhered or otherwise attached to the components of the platform.

FIG. 13 depicts an example a textured portion 1300. In this example, a plurality of scoops 1302 are defined in the surface 1304 of a component of the platform outside of the tread belt riding portion.

FIG. 14 depicts an example a textured portion 1400. In this example, a plurality of V-cuts 1402 are defined in the surface 1404 of a component of the platform outside of the tread belt riding portion.

FIG. 15 depicts an example a textured portion 1500. In this example, a plurality of raised sections 1502 are formed on the surface 1504 of a component of the platform outside of the tread belt riding portion.

GENERAL DESCRIPTION

In general, the disclosure herein is directed to a treadmill that can alert a user when the tread belt is off-center, off-center, or otherwise misaligned while in motion. A textured portion incorporated into the treadmill can mechanically produce a sound audible to a user when the tread belt is out of position in order to alert the user and allow the user to adjust the position of the tread belt.

The exercise deck may include a platform that has a first pulley located in a front portion of the deck and a second pulley located in a rear portion of the deck. A tread belt may surround the first and second pulleys and provide a surface on which the user may exercise. At least one of the first pulley and the second pulley may be connected to a motor so that when the motor is active, the pulley rotates. As the pulley rotates, the tread belt moves as well. The user may exercise by walking, running, or cycling on the tread belt's moving surface. In other examples, the tread belt is moved with the user's own power.

The exercise deck may be capable of having its front portion raised and lowered as well as its rear portion raised and lowered to control the lengthwise slope of the running deck. With these elevation controls, the orientation of the running deck can be adjusted as desired by the user or as instructed by a programmed workout. In those examples where the treadmill is involved with simulating a route that involves changes in elevation, the running deck can be oriented to mimic the elevation changes in the route.

The platform may include a sliding surface that includes tread belt riding portion. The tread belt riding portion may be aligned with a central portion of either the front pulley and/or the rear pulley, where the tread belt is intended to surround the pulleys while the pulleys rotate and the tread belt moves. In some cases, when the tread belt is misaligned either of the front or rear pulley, the tread belt is misaligned out of the tread belt riding portion of the sliding surface of the platform. However, in some cases, the pulleys, may become misaligned causing the tread belt to be misaligned with the tread belt riding portion. When the tread belt is maintained in the tread belt riding portion, the tread belt is generally subjected to an intended amount of natural wear from the motion of the belt and pulleys such that the tread belt may only need replacement relatively infrequently. For example, when the tread belt is maintained in the tread belt riding portion, the tread belt may experience substantially minimal wear along its edges. However, in some cases, for example during routine use of the treadmill or due to lateral forces exerted on the tread belt by a user, the tread belt may become displaced such that a portion of the tread belt may be outside the tread belt riding portion while the tread belt is in motion. In these cases the tread belt may be subjected to undue wear, for example along the edges of the tread belt. If the tread belt is allowed to remain in a displaced position during use, for example in situations where the user does not realize the tread belt has been displaced, the tread belt may experience such significant wear that it may need to be replaced well before the intended lifetime of the belt has lapsed. Further, in cases where the tread belt remains in a displaced position during use of the treadmill, the tread belt may experience reduced stability as compared to when the entirety of the tread belt is within the tread riding portion.

In some cases, the treadmill includes a belt guide which may produce an audible sound when a portion of the tread belt is outside of its intended position while in motion against the sliding surface to notify or warn a user. For example, the belt guide and the tread belt may collectively

produce a misalignment sound that is distinct and distinguishable by a user from the normal or routine operating sounds of the treadmill. In some embodiments the belt guide may mechanically produce an audible warning sound by contacting a portion of tread belt when it is displaced and in motion. In some cases, the belt guide may include a textured portion that contacts the tread belt when it has been displaced and is in motion. In some cases the mechanical action of the moving tread belt against the textured portion of the belt guide may produce the audible warning sound. As the treadmill including the audible belt guide produces an audible sound detectable by the user when the tread belt is displaced, the user may take appropriate action to realign or reposition the tread belt so that it is entirely within the tread belt riding portion. For example, the user may stop use of the treadmill and manually reposition the tread belt so that the tread belt is within the tread belt riding portion. As a consequence, the treadmill may not be used for a substantial duration with the tread belt out of position, and thus the tread belt may not experience undue wear that might have otherwise gone unnoticed. In this way, a treadmill including the belt guide as described herein may allow for reduced tread belt wear and longer tread belt life.

In one example, the treadmill may include a deck with a first pulley disposed in a first portion of the deck and a second pulley incorporated into a second portion of the deck. A tread belt surrounds the first pulley and the second pulley. A motor may be in mechanical communication with either the first pulley or the second pulley. A cover is superjacent the motor.

The treadmill may also include at least one belt guide that may audibly indicate to a user when the tread belt is off-center, off-center, or otherwise displaced from a belt riding portion of the first and/or second pulley while in motion. For example, the belt guide may mechanically produce a sound that is audible to a user when the tread belt is off-center or otherwise out of position around the first and/or second pulleys.

In some cases, the treadmill may include an upright structure that supports a console. The console may include incorporates at least one input mechanism and a display. The input mechanism can control at least one parameter of the treadmill, such as the speed of the tread belt, the incline of the deck, a climate control, entertainment, and so forth.

The platform may include a belt guide that includes a textured portion which may be aligned with one or both of the tread belt's edges. The textured portion may mechanically produce a sound, such as a misalignment sound, when the tread belt's edges are sufficiently out of position so that an edge of the tread belt contacts the textured portion of the belt guide. For example the textured portion may be spaced apart from an edge of the tread belt such that one of the tread belt's edges contacts the textured portion when the tread belt is sufficiently out of position. In some cases, this contact may mechanically produce the misalignment sound when the tread belt is in motion, for example, by continuously rubbing against the textured portion of at least one of the belt guides. In some cases, the deck may include a belt guide on the left side and/or the right side of the deck.

In some cases the textured portion of the belt guide or guides may be positioned at any position along the length of the belt guide and may be aligned with an edge of the tread belt. In some cases the textured portion of the belt guide may run an entire length of the belt guide. However in some other cases, the textured portion may extend along between about half of the length of the belt guide and the entire length of the belt guide. In some cases the textured portion may

extend along less than about half of the length of the belt guide, for example about $\frac{1}{3}$, $\frac{1}{4}$, $\frac{1}{8}$, $\frac{1}{16}$, $\frac{1}{32}$ or less of the length of the belt guide. In some embodiments the textured portion may not include one continuous portion and may be divided by one or more untextured portions of the belt guide. For example, the textured portion may include a first portion located near a first end of the belt guide and a second textured portion located near a second end of the belt guide.

The belt guide or guide may include a lip which extends over at least a portion of the tread belt and overlies the edge of the tread belt. In some cases, the textured portion of the belt guide may be positioned on an underside of the lip of the belt guide. However, in some other cases the textured portion may be located below the lip for example on the pulley or otherwise under the tread belt. In some cases, the textured portion may be positioned horizontally in line with an edge of the tread belt.

The tread belt may reside entirely within the central tread belt riding portion of the sliding portion. In some cases, when the tread belt stays entirely within the tread belt riding portion while in motion the life of the tread belt may be maximized. In some cases the tread belt riding portion may be wider than the tread belt to allow for some amount of lateral or vertical displacement of the tread belt without causing undue wear.

However, in some situations the tread belt may become displaced and some portion of it may become positioned outside of the tread belt riding portion. For example, in some situations the tread belt may become laterally displaced, such that an edge of the tread belt extends outside of the tread belt riding portion. In other cases the tread belt may become off-center, vertically displaced, or some combination of vertically and laterally displaced, as indicated with arrows, for example due to a fold in the tread belt, lateral forces from a user, or any other mechanism of action. Again, this displacement may lead the tread belt to rub against or otherwise contact portions of the treadmill outside of the tread belt riding portion such that the tread belt experiences undesirable amounts of wear.

In some cases the textured portion may be located at position on the belt guide. That is, in some cases, the textured portion may be aligned with an edge of the tread belt and may be spaced apart therefrom when the tread belt is entirely within the tread belt riding portion. In some cases where the belt guide includes a lip which extends over at least a portion of the edge of the tread belt, the texture portion may be located at position. That is, in some cases, the textured portion may be positioned in line with and above an edge of the tread belt. In some cases the textured portion may be located on the surface outside of the tread belt riding portion.

In some cases the textured portion of the belt guide may mechanically produce a sound audible to the user when a least a portion of the tread belt is positioned outside of the tread belt riding portion and the tread belt is in motion. In some cases when the tread belt is sufficiently displaced outside of the tread belt riding portion while in motion, the tread belt may contact and rub against the textured portion of the belt guide. In some cases the texture may be selected to mechanically produce a sound audible to the user when the tread belt contacts and/or rubs against the textured portion while the tread belt is in motion. In some cases, the textured portion may include a textured surface. For example, the textured portion may include a plurality of protrusions, ribs, ridges, or otherwise raised portions. In some cases, the textured portion may include ribs that are arranged perpendicular to at least one edge of the tread belt.

11

In some cases, the textured portion may include a patterned surface, and the pattern may be selected to produce a desired noise that is audible to the user. For example, the textured portion may include a regular pattern or a repeating pattern selected to produce a distinctive noise, such as a high pitched noise. In some cases, the textured portion may include an irregularly patterned surface. In some cases, the textured portion may include a rough or non-smooth surface. In some cases where the textured portion includes a rough surface, the surface may have a roughness (calculated as the arithmetical mean deviation of the assessed profile, R_a) of more than about 1 micron, more than about 2 microns, more than about 5, 10, 25, 50, or 100 microns or more.

In some embodiments, the textured portion may be formed as part of the molding process of forming the belt guide. That is, a negative profile of the textured portion may be incorporated into the mold of the belt guide where the belt guide is formed by a molding process. In some cases, the textured portion may be formed by other manufacturing processes, such as subtractive processes, or any process known in the art or developed in the future.

In some embodiments, as the tread belt contacts or rubs against the textured portion, the rubbing between the tread belt and the textured portion may mechanically produce a misalignment sound. In some cases, the sound may be readily distinguishable by the user from the normal operating sounds of the treadmill, for example the sound may be distinguishable from the sounds produced by the motor, the pulleys, the tread belt riding on the pulleys, and any other routine operating sounds. In some cases, the sound is a misalignment sound, and may be readily perceived as such by the user. For example, in some cases the sound may be a high pitched warning sound. In some cases, the textured surface may be selected to produce a sound that is not pleasant to the user in order to deter the user from operating the treadmill while a portion of the tread belt may be positioned outside the tread belt riding portion. In some cases, the sound is not produced by electronic means. That is, in some cases, the sound is produced solely via the mechanical action between the textured portion and some portion of the tread belt contacting the textured portion while in motion.

The treadmill may make operational sounds during while the treadmill is in use that are distinguishable from the misalignment sounds. For example, the motion between the sliding surface and the underside of the tread belt may make an operational sound. But, the operational sound is distinguishable from the misalignment sound. For example, the misalignment sound may have the characteristic of having a different frequency, a different pitch, a different amplitude, another different characteristic, or combinations thereof.

In some embodiments, the textured portion is positioned such that vertical displacement of the tread belt may cause a portion of the tread belt to contact the textured portion. Such a displacement may be caused, for example, by a fold in the tread belt, or by the tread belt becoming off-center. When the tread belt is in motion the top surface of the tread belt rubs against the textured portion to thereby mechanically produce a sound audible to and distinguishable by a user. In some embodiments where the belt guide includes a lip, the lip may be low enough such that the top surface of the tread belt may contact the lip and textured portion when the tread belt is laterally displaced and is not vertically displaced.

In some embodiments, an interior surface of the tread belt may contact with the textured portion. When the tread belt is in motion at least a portion of the interior surface of tread

12

belt rubs against the textured portion to mechanically produce a sound audible to and distinguishable by a user. In some cases, the opposing side of the treadmill may also include a belt guide having a textured portion. The inclusion of a second belt guide may thus enable the treadmill to mechanically produce a noise when the tread belt is laterally displaced in two directions.

Several exemplary locations for the textured portion of the belt guide are described herein, however other locations 10 of textured portion are expressly contemplated. In some cases any location that may contact the tread belt when at least a portion of the tread belt is outside of the tread belt riding portion, including being vertically displaced above the tread belt riding portion of the pulley may include a 15 textured portion to thereby mechanically produce a sound audible to a user as described herein. Further, any combination of the locations of the textured portion is expressly contemplated, such that in some embodiments the treadmill may include a plurality of textured portions on a belt guide. 20 In some examples, multiple textured portions may be included so that vertical, lateral, or any combination or vertical and lateral displacement of the tread belt outside of the tread belt riding portion may bring a portion of the tread belt into contact with a textured portion.

25 Further, although the belt guide is depicted as including a lip which overlies a portion of the edge of the tread belt, in some cases the belt guide may not include a lip. In some cases, the belt guide may include a vertical surface aligned with a spaced apart from the tread belt, such as ledge or rim. 30 In other cases, the belt guide is flush with the sliding surface of the platform.

In some cases, the treadmill includes a console. The console may locate the input mechanism within a convenient reach of the user to control the operating parameters of the 35 exercise deck. For example, the control console may include controls to adjust the speed of the tread belt, adjust a volume of a speaker integrated into the treadmill, adjust an incline angle of the running deck, adjust a decline of the running deck, adjust a lateral tilt of the running deck, select an 40 exercise setting, control a timer, change a view on a display of the control console, monitor the user's heart rate or other physiological parameters during the workout, perform other tasks, or combinations thereof. Buttons, levers, touch screens, voice commands, or other mechanisms may be 45 incorporated into the control console incorporated into the treadmill and can be used to control the capabilities mentioned above. Information relating to these functions may be presented to the user through the display. For example, a calorie count, a timer, a distance, a selected program, an incline angle, a decline angle, a lateral tilt angle, another type of information, or combinations thereof may be presented to the user through the display.

The treadmill may include preprogrammed workouts that 50 simulate an outdoor route. In other examples, the treadmill has the capability of depicting a real world route. For example, the user may input instructions through the control console, a mobile device, another type of device, or combinations thereof to select a course from a map. This map may be a map of real world roads, mountain sides, hiking trails, beaches, golf courses, scenic destinations, other types of locations with real world routes, or combinations thereof. 55 In response to the user's selection, the display of the control console may visually depict the beginning of the selected route. The user may observe details about the location, such as the route's terrain and scenery. In some examples, the display presents a video or a still frame taken of the selected area that represents how the route looked when the video

13

was taken. In other examples, the video or still frame is modified in the display to account for changes to the route's location, such as real time weather, recent construction, and so forth. Further, the display may also add simulated features to the display, such as simulated vehicular traffic, simulated flora, simulated fauna, simulated spectators, simulated competitors, or other types of simulated features. While the various types of routes have been described as being presented through the display of the control console, the route may be presented through another type of display, such as a home entertainment system, a nearby television, a mobile device, another type of display, or combinations thereof.

In addition to simulating the route through a visual presentation of a display, the treadmill may also modify the orientation of the running deck to match the inclines and slopes of the route. For example, if the beginning of the simulated route is on an uphill slope, the running deck may be caused to alter its orientation to raise the front portion of the running deck. Likewise, if the beginning of the simulated route is on a downward slope, the rear portion of the running deck may be caused to elevate to simulate the decline in the route. Also, if the route has a lateral tilt angle, the running deck may be tilted laterally to the appropriate side of the running deck to mimic the lateral tilt angle.

As the user begins to walk or run on the running deck, the display may change the scenery to mimic what the user would see if the user were actually at the real world location of the selected route. For example, a tree or another object located along the route that appears to be in the distance when the user is simulated to be at the beginning of the route may appear progressively closer as the user walks or runs on the running deck based on the speed at which the user is simulated to be traveling. Additionally, as the inclines and slopes of the simulated route change as the user progresses along the simulated route, the running deck can adjust to account for these terrain changes. For example, if the steepness of an uphill incline increases in the route, the running deck can likewise increase the incline of the running deck to mimic the change in steepness. Further, if the lateral angle of the route changes, the running deck can tilt laterally to one side to mimic the route's lateral angle.

While the programmed workout or the simulated environment may send control signals to orient the deck, the user may, in some instances, override these control signals with inputs from the console. For example, if the programmed workout or the simulated environment cause the deck to be steeper than the user desires, the user can adjust the deck's orientation through the console.

What is claimed is:

1. A treadmill, comprising:

an exercise deck, the exercise deck including:

a platform;

at least one pulley attached to the platform;

a sliding surface of the platform;

a tread belt riding portion defined in the sliding surface; 55

a tread belt surrounding the at least one pulley and the sliding surface, the tread belt having at least one edge; and

a belt guide incorporated into the platform, the belt guide including:

a textured portion aligned with the at least one edge of the tread belt and spaced apart therefrom when the tread belt is positioned entirely within the tread belt riding portion;

wherein when the textured portion comes into contact 65 with the tread belt due to the tread belt being misaligned with the tread belt riding portion, the

14

tread belt and the textured portion interact to collectively produce a misalignment sound audible to a user.

2. The treadmill of claim 1, wherein the textured portion includes a plurality of ribs.

3. The treadmill of claim 2, wherein the plurality of ribs are arranged perpendicular to the at least one edge of the tread belt.

4. The treadmill of claim 1, wherein the belt guide includes a lip portion extending over at least a portion of the at least one edge of the tread belt.

5. The treadmill of claim 4, wherein the textured portion is positioned above the at least one edge of the tread belt.

6. The treadmill of claim 1, wherein the textured portion includes a plurality of protrusions.

7. The treadmill of claim 1, wherein the textured portion includes a rough surface having a Ra surface roughness of more than about 5 microns.

8. The treadmill of claim 1, wherein the textured portion includes a patterned surface.

9. The treadmill of claim 1, wherein the tread belt and the tread belt riding portion collectively produce an operating sound audible to the user when the tread belt is in motion with respect to the sliding surface when the tread belt is not in contact with the textured portion;

wherein the operating sound produces a different frequency than the misalignment sound.

10. The treadmill of claim 1, wherein the belt guide includes a raised ledge aligned with the at least one edge of the tread belt.

11. The treadmill of claim 1, wherein the textured portion contacts the at least one edge of the tread belt to mechanically produce the misalignment sound when the tread belt is in motion around the sliding surface and at least a portion of the tread belt is positioned outside the tread belt riding portion.

12. The treadmill of claim 1, wherein the textured portion contacts an interior pulley facing surface of the tread belt to mechanically produce the sound audible to the user when the tread belt is in motion around the at least one pulley and at least a portion of the tread belt is positioned outside the tread belt riding portion.

13. The treadmill of claim 1, wherein the misalignment sound is not produced when no portion of the tread belt is positioned outside the tread belt riding portion.

14. The treadmill of claim 1, wherein the misalignment sound is distinguishable by the user from routine operating sounds of the treadmill produced when the tread belt is entirely positioned within the tread belt riding portion.

15. A treadmill, comprising:

an exercise deck, the exercise deck including:

a platform;

at least one pulley attached to the platform;

a sliding surface of the platform;

a tread belt riding portion defined in the sliding surface;

a tread belt surrounding the at least one pulley, the tread belt having at least one edge; and

a belt guide incorporated into the platform, the belt guide including:

a textured portion aligned with the at least one edge of the tread belt and spaced apart therefrom when the tread belt is positioned within the tread belt riding portion;

wherein the textured portion contacts the tread belt mechanically producing a misalignment sound audible when the tread belt is in motion with respect

15

to the sliding surface and at least a portion of the tread belt is positioned outside the tread belt riding portion;
wherein the misalignment sound is not produced when the tread belt is positioned entirely within the tread belt riding portion and the misalignment sound is distinguishable from a routine operating sound of the treadmill.

16. The treadmill of claim **15**, wherein the belt guide includes a lip portion extending over at least a portion of the ¹⁰ at least one edge of the tread belt.

17. The treadmill of claim **16**, wherein the textured portion is positioned above the at least one edge of the tread belt.

18. The treadmill of claim **15**, wherein the belt guide ¹⁵ includes a raised ledge aligned with the at least one edge of the tread belt.

19. The treadmill of claim **15**, wherein the textured portion engages an underside surface of the tread belt when the tread belt is misaligned out of the tread belt riding ²⁰ portion.

20. A treadmill, comprising:
an exercise deck, the exercise deck including:
a platform;
a first pulley attached to the platform in a front portion; ²⁵
a second pulley attached to the platform in a rear portion;

16

a sliding surface of the platform;
a tread belt riding portion of the sliding surface;
a tread belt surrounding the first pulley, the second pulley, and the sliding surface, the tread belt having at least one edge and a top surface; and
a belt guide incorporated into the platform, the belt guide including:
a lip portion extending over at least a portion of the at least one edge of the tread belt;
a textured portion including a rough surface, the textured portion aligned with and positioned above the at least one edge of the tread belt and spaced apart therefrom when the tread belt is positioned within the tread belt riding portion;
wherein the textured portion contacts the top surface of the tread belt to thereby mechanically produce a misalignment sound audible to a user when the tread belt is in motion with respect to the sliding surface of the platform and at least a portion of the tread belt is positioned outside the tread belt riding portion;
wherein the misalignment sound is not produced when the tread belt is positioned entirely within the tread belt riding portion and the misalignment sound is distinguishable by the user from a routine operating sound of the treadmill.
